US0D1013586S

(12) **United States Design Patent** (10) **Patent No.:** **US D1,013,586 S**
(45) **Date of Patent:** **** Feb. 6, 2024**

(54) **PROTECTIVE GRILLE FOR VEHICLE**

(71) Applicant: **MANITOU ITALIA S.R.L.**,
Castelfranco Emilia (IT)

(72) Inventor: **Simone Bonaretti**, Scandiano (IT)

(73) Assignee: **MANITOU ITALIA S.R.L.**,
Castelfranco Imilia (IT)

(**) Term: **15 Years**

(21) Appl. No.: **29/809,958**

(22) Filed: **Sep. 30, 2021**

(30) **Foreign Application Priority Data**

Apr. 2, 2021 (EM) 008483721-0003

(51) **LOC (14) Cl.** **12-16**

(57) **CLAIM**

The ornamental design for a protective grille for vehicle, as shown and described.

DESCRIPTION

FIG. 1 is a back-left side-top perspective view of a protective grille for vehicle, showing the new design;

FIG. 2 is a front-left side-top perspective view thereof;

FIG. 3 is a left side view thereof; the right side view being a mirror image thereof;

FIG. 4 is a back view thereof;

FIG. 5 is a bottom view thereof;

FIG. 6 is a front view thereof; and,

FIG. 7 is a top view thereof.
